CLAIM

The ornamental design for a helmet accessory dome light, as shown and described.

DESCRIPTION

FIG. 1 illustrates a top perspective view of a helmet accessory dome light showing my new design.

FIG. 2 illustrates a top view of the helmet accessory dome light.

FIG. 3 illustrates a bottom perspective view of the helmet accessory dome light.

FIG. 4 illustrates a bottom view of the helmet accessory dome light.

FIG. 5 illustrates the side views of the helmet accessory dome light: the front, back, left, and right-side views are all identical; and,

FIGS. 6 through 11 illustrate perspective views of the helmet accessory dome light in use.

The broken lines in FIGS. 3 and 4 illustrate portions of the helmet accessory dome light that form no part of the claimed design. The broken lines in FIGS. 6-11 illustrating various helmet styles represent environmental subject matter that forms no part of the claimed design.
